UNITED STATES PATENT OFFICE.

WINFRED ELMO REAVIS, OF LOS ANGELES, AND ELMER E. FREY, OF LONG BEACH, CALIFORNIA, ASSIGNORS TO OVERSEWING MACHINE COMPANY, A CORPORATION OF CALIFORNIA.

BOOK-SEWING MACHINE.

Application filed April 5, 1920. Serial No. 371,474.

To all whom it may concern:

Be it known that we, WINFRED ELMO REAVIS, of Los Angeles, California, and ELMER E. FREY, of Long Beach, California, have invented a certain new and useful Book-Sewing Machine, of which the following is a specification.

This invention relates to a machine for sewing books, and it has especial reference to an improvement in that type of machine described in those certain patents issued to John Griesinger, April 21, 1914, No. 1,093,694 and May 21, 1918, No. 1,266,793, and pertaining to the oversewing of the signatures in the making of a book.

One of the chief aims of the present invention is to obviate the troublesome, annoying and continual breakage of punches and needles employed in the oversewing of paper. We have found that the punching elements have a tendency to be diverted from a true course and to be deflected into the thinner edge portions of the stock, resulting, if this deflection is great enough, in the breakage of some of the punches, and in any event in producing a penetration of the paper swerving from a straight line. The needles entering into the penetrated stock, and of necessity, following the perforations, are likewise deflected, and as a consequence, are bent or broken. Thus poor loop formation and defective sewing are noticeable, especially in cases of hard, dense papers.

An object of the invention, therefore, is to provide a means, in connection with a book sewing machine, in which the penetration of the stock shall occur in a perfectly straight line and in which the sewing shall be practically perfect.

A further object of the invention is to provide in connection with an oversewing machine, a clamping mechanism, by which the stock or signatures may be subjected to variable pressures during the various operations of the stitch-forming mechanism, to the end that the variable counter pressures of punches may be withstood by a pressure continuing during such operation and varying after such operation.

These and other objects are accomplished by the preferred form of embodiment of the

invention illustrated in the accompanying drawings, in which:

Fig. 1 is a rear view of the machine, with 55 certain minor parts omitted.

Fig. 2, is a section, approximately on line 2—2, Fig. 3.

Fig. 3, is a front view of the machine.

Fig. 4 is a fragmentary sectional view of 60 the pressure distributing means, shown in operative or elevated position, the section being taken on line 4—4, Fig. 16.

Fig. 5, is a fragmentary sectional view of 65 the pressure distributing means shown in inoperative or normal position, the section being taken on line 5—5, Fig. 16.

Fig. 6, is an end view of the complementary clamp table, showing the pressure distributing means; the thread severing and 70 clamping means; the main clamp table being shown in section. The view also shows in perspective, a series of sewed signatures, with the threads severed.

Fig. 7, is a plan view showing the operating mechanism for the lock thread needles, and also showing a means for catching and holding the lock threads.

Fig. 8, is a front view of the sliding frame carrying the punches and the needles.

Fig. 9, is a fragmentary section on line 9—9, Fig. 7, showing the cross-thread holding or retaining pins in normal or inoperative position, and the normal position of the actuating means therefor.

Figs. 10 and 11, respectively, are fragmentary front and side views of the cross-threads holding pins and the actuating means therefor, in the positions they occupy during the punching operation.

Fig. 12, is a fragmentary front view, showing the cross-thread holding pins retaining the cross-threads and the plunger for actuating the pins, the plunger being in a position immediately preceding its operation of withdrawing the pins from the cross-threads.

Fig. 13, is a fragmentary side view of Fig. 12.

Fig. 14, is an enlarged fragmentary detail, of the bar carrying the dies or bushings.

Fig. 15, is an enlarged fragmentary front view of same.

Fig. 16, is a plan view of the clamp table, showing more particularly the pressure distributing means, and the position of the complementary clamp table when opened by hand, during which opening, the sewed signatures are manually held and carried below the surface of the complementary table, preparatory to closing the same for severing the threads, as seen in Fig. 6. The open position of the complementary table is shown in dotted lines.

Fig. 17, is a fragmentary view of the complementary knife carried in the main clamp table.

Fig. 18, is a detailed front view of the complete clamping and shifting mechanism for the signatures.

Fig. 19, is a sectional view taken on line 19—19, Fig. 18.

Figs. 20 and 21, respectively are fragmentary sectional views showing a means of locking the main clamp head to the side frames of the machine.

Figs. 22, 23, 24 and 25, are fragmentary sectional views, respectively showing the clamping and sewing mechanism during four stages of operation.

Fig. 26, is a plan view showing the cross-thread-needles and the cross threads retaining pins in operative position.

Fig. 27, is a similar view showing cross-thread needles and the cross-threads retaining pins in withdrawn position, and the sewing threads tightened upon the lock or cross-threads.

Fig. 28, is an enlarged front view, partly broken, showing the mechanism for shifting the signatures to cause the stitches to be made out of alinement.

Fig. 29, is a fragmentary sectional detail of the shifting mechanism shown in Fig. 28.

Fig. 30, is a section on line 30—30, Fig. 28, showing the operating arrangement for the shifting mechanism.

Fig. 31, is a projected view of the cam track for actuating the shifting mechanism.

Fig. 32, is a sectional view approximately on line 32—32, Fig. 1.

Fig. 33, is a series of perspective illustrations showing the steps followed in the sewing together of the first four signatures.

Fig. 34, is a series of end views showing the location of the stitches in the building up of a book.

Fig. 35, is a diagrammatic view illustrating the relative arrangement of stitches as made by this machine.

Figs. 36, 37, 38 and 39, are fragmentary sectional views, illustrating the relative positions of the local signature-supporting means.

Fig. 40, is a fragmentary, enlarged perspective view showing insert attached to the clamphead for supporting the signatures, and also showing the lock thread

supporting means, when short signatures are being sewed, and

Fig. 41, is an enlarged, fragmentary perspective view illustrating a means of spacing sewed books from signatures to be sewed, without severance of the threads.

The frame consists of two spaced uprights 1 and 2, conjoined by tie rods 3 and 4, or in any other suitable manner, and also by a cross-member 5, on to which is bolted or otherwise secured, a bar 6, formed with a face 7, at an angle to the horizontal, and with a projecting ledge 8, under which the signatures are arranged to be placed and supported during the sewing process.

This bar 6, is provided with a plurality of dies 9, held in place, as by means of screws 10, and extending for a short distance beyond, and having the same angularity to the horizontal as the face 7. Vertical perforations 11, in the bar 6, and extending through and to the inclined face of the dies 9, serve as needle guides; and perforations 12, extending at an angle to the horizontal, through the dies 9, and terminating above the needle guides 11, serve to guide and support a local signature-supporting and compression-equalizing means, hereinafter more specifically referred to. The spaced uprights 1 and 2, are each provided with channels 14 and 14', in which is reciprocable, by means presently set out, a slide frame 15, composed of two spaced bars A and B, conjoined by yokes 16 and 16', the bars respectively carrying a punch bar 17, and a needle bar 18.

In the bar 17, are adjustably fixed a plurality of punches 19, which operate through a punch guide bar 20, yieldingly associated with the punch bar 17, in any suitable manner, as by springs 21, fixedly secured in the punch guide bar 20, and extending into the punch bar 17, holding the punch guide bar 20 under tension and spacing the same.

Additionally, guide pins 23 are fixedly mounted in the punch guide bar 20 and operate slidably through the punch bar 17 and through the bar 6. The needle bar 18, carries a plurality of adjustable needles 24. The reciprocation of the slide frame 15, is effected by cam wheels 25 and 25', secured on the main driving shaft 26, the slide frame being provided with studs 27 and 27', extending in the grooves of the cam wheels. The cross-member 5, aforesigned, carries a shaft 5', upon which are mounted bevel gears 28 and 29, meshing with complementary gears 30 and 31, respectively, mounted on spindles extending transversely through the cross-member and provided with pinions 32 and 33, respectively, in mesh with racks 34 and 35, respectively, to which are yoked, or otherwise secured, horizontally disposed lock thread needles 36 and 37, respectively, which are periodically moved forth and

back to provide the necessary lock threads for the stitches, by pinion 38, on the shaft 5' and in mesh with a rack 39, on one end of a rod 40, the other end thereof being pivotally connected to a lever 41, pivotally mounted on a shaft 42, and carrying a fulcrum pin 43, disposed in the groove 44 of a cam 45, which is mounted on the main shaft 26, and which periodically reciprocates the said rack 39. Loop penetrating means, to hold the lock or cross-threads during the withdrawal of the cross-needles 36 and 37, may comprise a plurality of pins 46, mounted on a slide 47, having a beveled edge 48, and operable through the cross-member 5. This slide 47, Fig. 26, is provided with a stem 49, carrying a projection 50, against which the tension of a spring 51, is exerted to move the pins 46, into operative position, as shown in Fig. 7, when thus required, the slide 47 being held in normally inoperative position by a spring-pressed latch 52, pivotally supported on a bracket 53, on the cross-member 5, and having a tang 54, which is disposed in the path of travel of a beveled lug 55, on a disk 56, mounted on the shaft 5', for tripping the latch 52, and causing the slide 47, to be projected by the spring 51, and the pins 46, to be thrust into the loops of the cross-threads. The ejection of the pins 46, after the tightening of the loops upon the cross-threads, is effected by the beveled end of a plunger 57, secured in the punch bar 17, and arranged to engage the beveled edge of the slide 47, when moved downwardly by the punch bar 17. Such engagement removes the pins 46, from the cross-threads and resets the slide 47. Pivotally mounted upon each of the racks 34 and 35, is a roller 58 and 59, which traveling with the cross-needles 36 and 37, supplies a suitable lubricant to the ends of the punches 19. Eyelets 60 and 61 are preferably provided on the cross-member 5, for guiding the lock threads from the spools 62 and 63.

The cam grooves of the cam wheels 25 and 25', aforementioned, perform the function of moving the slide frame 15, in vertical strokes of varying and intermittent lengths, the periodicity of movement being governed and given by the cam grooves to effect the progression of steps required, to wit: the punching, the introduction of the needles into the punched material, the loop formation, and the needles' withdrawal.

Referring to Figs. 22, 23, 24 and 25, and especially to Fig. 25, and assuming that the cams 25 and 25', and the parts to be actuated thereby are in normal position or in a position of rest, during which a new signature is inserted for sewing upon previously sewed sections, the revolution of the cams in the direction of the arrow will draw down the frame 15, to the position shown in Fig.

22, for punching the signatures, the cam grooves, which actuate the slide frame for the punching movement gradually curving toward the axis thereof and effecting the lowest downward movement of the slide frame where the grooves are nearest the axis. The continued movement of the cam grooves, thereupon lifts the slide frame 15, by traverse of the studs 27 and 27', in the cam groove areas X, to the highest position, Fig. 23, carrying and introducing the needles 24 into the perforations made by the punches 19. As the cam grooves continue in their circulatory movement, the cam areas Y thereof, draw down the slide frame for a limited extent and effect a partial withdrawal of the needles for a distance sufficient to form loops 64, Fig. 24, the needles and slide frame being now held in stationary position by the cam groove areas Y', which as seen, are substantially concentric with the axis thereof. During such halt of the needles and slide frame, the horizontal lock thread needles 36 and 37, are operated and passed through the loops 64, as seen in Fig. 26, and then withdrawn. The continued rotation of the cam grooves thereupon effects a further downward movement of the slide frame, whereupon, after the withdrawal of the cross-thread needles, the loops 64 are tightened upon the cross-threads and the position of the punch and needle bars is substantially that shown in Fig. 25, in which position, the insertion of a new signature upon a previously sewed one takes place.

Co-operating with the reciprocating slide frame 15, Fig. 2, is the principal tensioning means, comprising, as seen in Figs. 2 and 32, a plurality of arms 244, secured on the shaft 232. These arms 244, are connected by a rod 245, under which the threads 238 run to the needles after passing through tension devices 246. On the shaft 232 is secured a lever 247, the end of which is provided with a roller 248, which bears against a cam 133, that operates the tensioning means for obvious purposes.

Suitable means for operating the tension devices 246, to relieve the frictional pressure thereof from the threads 238, when required, may be provided, and for purposes of this description, may comprise a plurality of fingers 251, mounted on a rod 252, carried in suitable bearings and under tension longitudinally of a spring 253. Pivotally connected to one end of said rod 252, is a bell-crank lever 254, suitably fulcrumed, and controllably connected to a rod 255, pivotally connected to pedal 256, on a stationary shaft 257.

On the main stationary shaft 42, is mounted a main plate C, provided with lugs 64', 64'', by which the main plate C is arranged to swing, for purposes hereinafter appear-

ing. This main plate C, is formed with a clamp head 65, with which a clamp table 66, co-operates in effecting the clamping of the signatures.

5 On the bottom of the main plate C, is formed a plurality of ears 129^a, for pivoting a rod 230, connected at one end to a bell-crank 231, on a shaft 232. To the other end of the bell crank 231, is pivotally connected a link 233, which in turn is attached to a lever 233', integral with a sleeve 234, on a shaft 235. Upon the shaft 235, Figs. 2 and 32 is secured a plurality of arms 236, connected by a rod 237, over which the threads 238 are run from the tensioning means. The mechanism hereinabove detailed operates to relieve the tension of the threads when the main plate C is swung forward upon the shaft 42, for access to the needles for the purpose of threading or removing them.

Referring to Figs. 36, 37, 38, 39 and 40, a suitable support may be provided for the signatures, and this support may comprise 25 a sheet of metal 128^c, bent upon itself at right angles, the portion 128^c, thereof lying between the clamp table plate 68 and the main plate C, and provided with a plurality of openings 128^b, into which fit the extended dies 9. The portion 128^c, of said sheet 128, extends under and is fastened securely to the clamp head 65. Such portion 128^c is provided with a longitudinal slot 128^d for permitting the passage therethrough of 35 the punches and needles.

The clamp table 66, is operable in guide ways 67, on the main plate C, and has attached thereto a plate 68, slidably disposed in guides 69, on the main plate C Figs. 18, 40 19 and 22 to 25, and arranged to be held in clamped or stationary position, by pressure plates 70 and 71, operable by a draw bolt 72. This draw bolt 72, as hereinafter explained, is under the control of an eccentric 73 and 45 a lever 74. Suitable friction liners 70' and 71' may be placed between the pressure plates 70 and 71, and the plate 68, of the clamp table to insure a firm and proper hold upon the clamp table during the clamping 50 operation. Springs 70" may also be provided for disturbing the adherence of the liners 70' and 71' to the plate 68, when the pressure of the presser plates is relieved, and enabling the plate 68 to be moved relatively 55 to said liners.

A screw head 75, on the draw bolt 72, serves to predetermine the pressure of the presser plates 70 and 71 upon the plate 68, of the clamp table 66. The presser plates 70 60 and 71, with the clamped plate 68 are movable relatively to the main plate C by a sleeve bell-crank 76, on the main stationary shaft 42, which bell-crank, extends through an aperture 77, in the main plate C, as does 65 also the draw bolt 72. The sleeve bell-crank

is loosely mounted upon the stationary shaft 42, and the lower limb 78, thereof, is provided with a roller or idler 79, that rides over the periphery of a cam 80, on the drive shaft 26. This cam 80, see Fig. 25, is formed with a depression 80', into which the idler 79, fits, when the punch and needle bars are normally in the position in said Figure 25, or in a state of rest, during which a new signature is supplied for sewing. The cam 80, being then revolved, throws the idler 79, out of the depression 80', causing thereby the clamp table 66, to clamp the signatures between it and the clamp head 65. For a distance equal substantially to the distance required for the punching of the signatures, the periphery of the cam 80, is eccentric, the eccentricity beginning at the apex of the depression 80' and continuing for a predetermined extent until the concentric portion of the cam is reached, as shown in Figs. 22, 24, 25 and 32. During such movement of the cam 80, the presser plates 70 and 71, move relatively to the clamp plate 68, of the clamp table 66, which is thereby subjected to a continuing active pressure during the punching operation, and such continuing pressure enables a proper and effective clamping of the signatures throughout, and compensates the counter pressure exerted by the punches during the punching operation.

Herein the expression "continuing active pressure" is intended to mean a pressure that continues uniform during the punching operation, to offset or counterbalance the pressure of the punches, which are thereby enabled to perforate the signatures without deflection and breakage of the punches. This effect is to be distinguished from the passive pressure of a common clamp, which, after once being set, exerts only a passive pressure and could not counterbalance or offset the pressure of the punches, the tendency of which is to force away the signatures from one of the jaws of the clamp and thereby cause a deflection and breakage of the punches.

Local support for the signatures as and for the purpose herein set out, may be provided to effect the penetration of the stock in a straight and true line, and such support may comprise a plurality of series of tines 127, formed in a head 128, preferably integral with levers 129, pivotally connected to the ends of levers 130, integral with a sleeve 131, that is fulcrumed upon the shaft 232. Also integral with the sleeve 131, is a lever 130', pivotally connected to a link 243, which in turn, is pivotally connected to the end of a bar 240, operated intermediate its length by a cam 241, and having its other end fulcrumed in a hanger 242, on the main stationary shaft 42, and which cam 241 operates to project the tines 127 below or between the signatures or leaves, Figs. 36, 37, 130

38 and 39. The series of tines severally comprise each two or a pair of tines for each punch, that is two tines each of the series are projected under the signatures or leaves 5 prior to the punching of the stock, so that the punches will pass through the signatures and between the projected tines, which furnish the necessary substantial support during the punching operation.

10 It will be seen from the figures referred to that the supports or tines herein designated are introduced between the signatures or leaves and in planes parallel with the signatures and in the area of the exit of the 15 punching means, which obviously may be operated from above, as shown herein, or from below, if desired, in which event the local support for the signature to resist the upward direction of the punches, will be furnished by the sheet metal portion 128°.

Onto the main clamp table 66, is hingedly secured a table 66', complementary to table 66, and arranged to swing at right angles thereto, for purposes to appear herein-after. This complementary table 66', is slotted longitudinally for accommodation of a means for exerting pressure upon the signatures on a line parallelling and ahead of the backs thereof concurrently with the main 30 pressure upon the signature backs, with the essential end in view of pressure distribution for maintaining in perfect alinement the signature backs and preventing their undesirable and troublesome bowing and 35 arching during the sewing, it being evident that the backs of the books build most rapidly during the sewing operation. The means for this purpose may comprise generally any arrangement that will contribute 40 this pressure in or over the necessary area and may comprise a combination of elements, as shown in Figs. 4, 5 and 6, and specifically a sliding member 81, disposed and operable in the slot of said table 66', 45 and normally extended beyond one end of said table, and in line with an operating mechanism therefor, presently described. Upon this sliding member 81, is mounted a plurality of blocks 82, preferably wedge-shaped and corrugated on the inclined surfaces thereof and arranged to co-act with similarly shaped blocks 83, attached to the underside of the bar 84, disposed in an opening 85, in said table 66', and movable vertically relatively to the surface thereof by the wedge shape blocks 82 on the sliding member 81. The blocks 82 and 83 are corrugated, as shown in Figs. 4, 5 and 6, to cause an interlocking of same when under pressure, otherwise they would slip back to their normal positions, shown in Fig. 5, when pressure was applied to the bar 84. The actuation of the sliding member 81, is accomplished by the engagement of the extended end of the sliding member 81, with

a wedge abutment 86, formed integral with the main plate C, during the descent or fall of the clamp table 66, caused by the increasing thickness of the book. The return to normal position of the sliding member 81, 70 is brought about by the opening or movement of the complementary table 66', relatively to the table 66, in a manner and by the arrangement following:

The hinged bearing for the table 66', is 75 formed with an extension 87, having a curved portion 87', against which strikes the end of the sliding member 81, (projected on the other side of the complementary table 66' during the elevation of the bar 84), 80 when such complementary table is swung open.

Associated with said clamp table 66 and the complementary table 66' thereof is a thread cutting mechanism, performing in 85 addition the function of grasping or holding the upper ends of the severed threads. Secured in the edge of the complementary table 66', is a knife 88, of sufficient length to sever all the threads. Flexibly or resiliently secured in the clamp table 66 is a complementary knife 89, co-operating with the knife 88 to produce a shearing action. This complementary knife is disposed below the surface of the table 66, and rearwardly of the front edge, and is held in close engagement with the underside of the table by a plurality of springs 90, Fig. 6. One end of said complementary knife 89, is 90 curved or bent downwardly, Fig. 17, to permit of ready entrance of the knife 88, between the table and complementary knife 89. The disposition of the complementary knife rearwardly of the front edge of the table is for the purpose of causing the knife 100 88 to carry or push and clamp the various threads under the table prior to their severance and preparatory to sewing another book.

On the lower end of the slide or plate 68, 110 is fastened a bracket 97, to which are attached chains 98 and 98', running over idlers 99 and 99', on the main stationary shaft 42, and over the end of a journal 100, of the idler 79, Fig. 22.

The ends of the chains 98 and 98' are connected to a weight 101, which operates, first, to move or elevate the clamp table 66 to normal position, when the presser plates' pressure is relieved, and second, to hold the 120 idler 79 in contact with the face of the cam 80.

Referring to Figs. 34 and 35, it will be seen that the series of stitches are made out of alinement with each other or staggered, the aim being to avoid penetration or entrance of the needles in previously made thread carrying perforations. The mechanism for effecting this arrangement of the 125 stitches is shown in detail in Figs. 28, 29 130

and 30, and differs from mechanism heretofore employed in shifting the signatures relatively to the clamp table after each sewing operation instead of moving the entire 5 clamp table and complementary parts thereof. It differs further in that the active force for the shifting mechanism is stored during the punching and sewing operation, while the signatures are clamped, and the expenditure 10 of such force resisted by the signatures, when the book guide movement is toward the book, until the clamp is released; and this will appear more clearly from the following. The ends of the clamp head 65, 15 are turned to form substantially shafts 65' and upon one of said ends is mounted for revolution a sleeve 102, that is securely fastened to a cylinder 103, provided with a cam groove 104, divided into four offsets 20 a, b, c, and d, Fig. 31; the offsets b and d being approximately one and a half times longer than the offsets a and c, whereby the third stitch and the fifth or initial stitch of the following series will be made at a 25 point removed approximately one and half times the distance between the first and second stitches. The fourth stitch will then occur at a point between the third and near the second stitch, as shown in Fig. 35. On 30 to the end of the cylinder 103, is fastened a four step ratchet wheel 104', with which a spring pressed pawl 105 co-operates. This pawl 105 is pivotally secured to a strap 106, surrounding the barrel or cylinder 103, and 35 to the strap 106, is pivotally connected a link 107, which in turn is pivotally joined at its lower end to a rod 108, pivotally secured to one of the yokes 16, Fig. 3.

When the yoke 16 is moved downwardly 40 with the frame 15, in the manner and for the purpose described, the pawl 105 on the strap 106, is carried behind one of the ratchet teeth of the wheel 104. The axial movement of the cam cylinder 103, likely 45 to result from the frictional engagement of the pawl with the ratchet wheel 104, is prevented by a ball 109, arranged to seat seriatim in pockets 110, formed on the inside of the sleeve 102. This ball is under 50 tension of a spring 111, disposed in a recess 112, in the shaft 65', of the clamp 65. When the yoke 16 is moved upwardly, the pawl 105 revolves the cam cylinder for a 55 distance equal to one of the offsets, and in so doing, effects the movement of the signatures under the following conditions and by the following arrangement, shown in detail in Fig. 28.

On the clamp head 65 is fixed, by any 60 suitable means, as a bracket 113, a housing 114, provided with a slot 115. In this housing 114, is contained a slide 116, provided with a pin 117, which projects through said slot 115 and into the cam groove 104, of the

cylinder 103. The slide is formed with a cavity 118, in which is operatively disposed the head 119 of a rod 120, which extends through a bore in the said slide 116, and around which is coiled a spring 121, located between the end of said slide and a collar 122, formed on said rod 120. On said rod is a shifting means 123, which for purposes of this description, may comprise a member 124, adjustable on said rod 120, and held in position of adjustment by a set screw 125, Fig. 28. Extended vertically through said member 124, and in close proximity to the surface of the clamp table 66, is a push rod 126, against which the signatures are placed. The other end of the rod 120 is supported 80 in a bearing 127, and is also under the tension of an auxiliary spring 128^e coiled thereabout, and bearing against the collar 129^b, thereon, for assisting the spring 121, in moving the signatures. 85

When the machine is set in operation, the signatures are first clamped; then the same are punched by the downward movement of the punch bar 17, and during such downward movement, which includes the movement of the yoke 16, the pawl 105 is drawn behind one of the teeth of the ratchet wheel 104. During the upward movement of the needle bar 18, for carrying the threads through the perforations made by the punches, the pawl 105, moves the cam cylinder 103, a quarter of a revolution, thereby causing the slide 116, to be moved one step by the cam groove 104 and in so doing, pulls the rod 120, the collar 122 of which compresses the spring 121 on the rod 120. This occurs, as will be seen when the cam groove 104 carries or moves to the right through two of its steps. The slide 116, pulling on the head 119 of the rod 120, draws the latter and the shifting means and the push rod 126 away from the book signatures. The operator pushes the signatures to the right against the push rod 126. But, when the cam groove 104 carries or moves to the left 105 through the remaining two steps, the slide 116 presses against the spring 121, and because at that moment the book clamp is closed and the push rod 126 is against the clamped signatures, the rod 121 remains 110 stationary and the slide moves to the left and compresses the spring 121. When then the book clamp is opened, the spring 121, pressing on the collar 122 and assisted by the spring 128^e, which is compressed against the collar 129^b, pushes the rod 120 with the shifting means 123 and the push rod 126 115 mounted thereon, to the left and moves the signatures the distance of one step of the cam groove 104. The shifting means herein 120 described moves the signatures to the left 125 only. It determines the positions of the signatures by the manual movement to the

right, but the operator must move the signatures against the push rod. In this manner and by the series of rectilinear movements performed automatically and 5 manually, with definite intervals of rest, staggered sewing is produced, as shown in Figs. 34 and 35.

Referring to Fig. 40, a means is employed to support the cross or lock threads, when 10 the needles used occupy a distance less than that substantially traversed by the cross thread carrying needles, and prevent the dropping down, snarling and accidental cutting of such cross threads. This means 15 may comprise lips 154, adjustably attached to the clamp head 65, and adapted to be set at various points upon the clamp head, in accordance with the width of the books to be sewed.

20 In Fig. 41 we have disclosed a method for the continuous sewing of books, that is for making unnecessary the removal of a book completely oversewed and preventing the sewing together of two or more books, 25 the object in view being to provide for continuous sewing without interruption, if desired.

The means for accomplishing this purpose, may comprise spacers or plates of any 30 suitable material 150, which are disposed between the oversewed books, in the manner shown in Fig. 41, and which are provided with vertical kerfs 151, through which the punches and needles may travel during the 35 sewing of the initial signatures of another book above one already sewed, and from which the stitching are not severed.

Referring to Figs. 1, 2, 3, 18, 19, 20 and 21, 40 a locking arrangement is shown for holding the main plate C in secure position during the sewing operation. This arrangement comprises preferably knobs 260 rotatably mounted upon the shafts 65', which, as stated, are turned on the clamp head 65. 45 Integral with said knobs 260, are latch arms 261, formed with intermediate notches 262, and with hooked ends 263, which ends are arranged for engagement with a rod 264, journaled in the side frames 1 and 2, for 50 the purpose of limiting the outward swing of the plate C. This rod 264 is formed with flattened ends 265 over which fit the notches 262, in the arms 261, for the purpose of locking home the main plate C by the following means:

Upon the tie rod 3, is fulcrumed a hand 60 lever 266, to one end of which is pivotally joined a link 267, pivotally connecting with an arm 268, fixedly mounted upon the rod 264, which is oscillated by the hand lever 266, whereby the flattened ends of the rod 264, are changed from the vertical position shown in Fig. 20, to the horizontal position shown in Fig. 21, in which position 65 the arms 261, are rigidly locked and

the main plate is drawn into position and firmly held.

What we claim, is:

1. In a book sewing machine, the combination with a stitch forming mechanism for signatures, of means for clamping the signatures, and means comprising a push member movable in opposite direction in stages for moving the signatures automatically in one direction, and permitting movement of the signatures in the opposite direction.

2. In a book sewing machine, the combination with a stitch forming mechanism for signatures, of means for clamping the signatures, means to operate said clamping means to impart to said signatures a variable pressure, and means comprising a push member movable in two stages in opposite directions for moving the signatures automatically in one direction and permitting the movement of the signatures in the opposite direction.

3. In a book sewing machine, the combination with a stitch forming and punching mechanism, of clamping means for the signatures, and means for causing the clamping means to exert a continuing active pressure upon the signatures, during the punching operation.

4. In a book sewing machine, the combination with a stitch forming and punching mechanism, of automatic clamping means for the signatures, and means for causing said clamping means to exert a variable pressure upon said signatures during the punching operation.

5. In a book sewing machine, the combination with a stitch forming mechanism, or a clamping means for the signatures, and means to cause said clamping means to exert variable pressures successively upon said signatures, during the punching operation.

6. In a book sewing machine, the combination with a stitch forming mechanism for signatures, of a clamp table supporting the signatures, a clamp head co-operating with said clamp table, means to hold the clamp table in position, and means to operate said holding means to cause said clamp table to exert varying pressures upon the signatures during the punching operation.

7. In a book sewing machine, the combination with a stitch forming mechanism for signatures, of a clamp table supporting the signatures, a clamp head co-operating with said clamp table, means to hold said clamp table in position, and means to operate said holding means at one time to exert a continuing active pressure upon the signatures during one step of the stitching operation, 125 and at another time to exert a varying pressure upon the signatures during another step of the stitching operation.

8. In a book sewing machine, the combination with a stitch forming mechanism for 130

signatures including a punching means, of a clamp table to support the signatures at an angle to the horizontal, a clamp head co-operating with said clamp table, and means independent of the clamp table to support the signatures in the plane of exit of the punching means.

9. In a book sewing machine, the combination with a stitch forming mechanism, including a punching means for signatures, of means in advance of the punching means to support the signatures locally during the punching thereof.

10. In a book sewing machine, the combination with a stitch forming mechanism including a punching means for signatures, of means actuatable in the plane of the signatures at or near the point of exit of said punching means for supporting the signatures during the punching thereof.

11. In a book sewing machine, the combination with a stitch forming mechanism including a punching means for signatures, of means actuatable in a plane transverse to the point of exit of the punching means and parallel to the signatures to support the signatures during the punching thereof.

12. In a book sewing machine, the combination with a stitch forming mechanism including a punching means for signatures, of means actuatable in the region of penetration of the punching means to support the signatures during the punching thereof.

13. In a book sewing machine, the combination with a stitch forming mechanism including a punching means for signatures, of means to operate said stitch forming mechanism, means to support the signatures in the region of penetration of the punching means, and means to move said supporting means to operative and inoperative positions respectively.

14. In a book sewing machine, the combination with a stitch forming mechanism including a punching means for signatures, of means actuatable in advance of the punching means to support the signatures counter to the punching means.

15. In a book sewing machine, the combination with a stitch forming mechanism including a punching means for signatures, of signature supporting means actuatable in the region of penetration of the punching means.

16. In a book sewing machine, the combination with a stitch forming mechanism including a punching means for signatures and a punch carrying bar, of means operable inwardly from opposite sides of the signatures to provide lock threads for the stitches and means to hold said lock threads during the recession of the lock thread providing means comprising a slide, a plurality of pins on said slide for penetrating

the loops of said cross threads, a latch for holding said slide and pins normally inoperative, means for tripping said latch to project said pins into the cross thread loops, and means on the punch bar for withdrawing the pins and resetting the slide.

17. In a book sewing machine, the combination with a frame, a stitch forming and punching mechanism, of a bar secured to said frame, dies in and extending beyond the face of said bar, said dies formed with vertical perforations serving as needle and punch guides, and with channels extending at an angle to the horizontal, means to hold said dies in place, and means operable through the channels of said dies to provide local support for and during the punching of said signatures.

18. In a book sewing machine, a punching means and a stitch-forming mechanism for signatures, means to operate the punching means and stitch forming mechanism, means to supply lock threads for the stitches, and means carried by said lock thread supplying means to lubricate the punching means.

19. In a book sewing machine, a stitch forming mechanism, means to operate said stitch forming mechanism, a clamping means for the signatures comprising a main table, a supplemental table movable relatively to said main table, and means on said tables co-operating to sever the threads and to hold the thread ends prior to the initial sewing of a succeeding signature of another book.

20. In a book sewing machine, a stitch forming mechanism for signatures, a clamping means for signatures, pressure distributing means associated with said clamping means, and means to operate said means, independently of said clamping means.

21. In a book sewing machine, a stitch forming mechanism for signatures, a clamping means for signatures, means associated with and movable relatively to the clamping means to effect a pressure upon the signatures concurrently with the clamping means, and means to operate said means.

22. In a book sewing machine, a stitch forming mechanism for signatures, a clamping means for the signatures, and means actuatable relatively to said clamping means to hold in alinement the back edges of the signatures to be sewed.

23. In a book sewing machine, a stitch forming mechanism for signatures, a clamping means for the signatures, and pressure distributing means for the signatures associated with and operable relatively to the clamping means.

24. In a book sewing machine, a stitch forming mechanism for signatures, means for exerting pressure upon the signatures,

independent means for exerting pressure upon a definite area of said signatures, and means to control said means.

25. In a book sewing machine, a stitch forming mechanism for signatures, means for exerting pressure upon one area of said signatures, means for simultaneously exerting pressure upon another area of said signatures, and means controllable by said 10 first named means for operating said last named means.

26. In a book sewing machine, a stitch forming mechanism including a punching mechanism for signatures, clamping means 15 for the signatures, and means for separating sewed books from signatures to be sewed without severance of the threads to prevent sewing together of two or more books, comprising spacers arranged to be 20 disposed between the sewed signatures and the signatures to be sewed, said spacers formed with vertical kerfs through which the needles and punches may pass.

27. In a book sewing machine, a stitch forming mechanism for signatures, a clamping 25 means for the signatures, means to

cause the clamping means to exert variable pressures upon said signatures, pressure means actuatable with said clamping means to compensate for variations in thickness 30 of the superimposed signatures, and means to supply lock threads from each end of the signatures.

28. In a book sewing machine, a stitch forming mechanism for signatures, a clamping means for the signatures, means to cause said clamping means to exert variable pressures upon said signatures, means associated with said clamping means to keep in alinement the back edges of the signatures, means to provide lock threads for the 35 stitches, means to move the signatures relatively to the clamping means and stitch forming mechanism to cause the stitches to be made out of alinement with each 40 other, and means to operate all of said means.

In testimony whereof we have set our hands.

W. ELMO REAVIS.
ELMER E. FREY.
